UNITED STATES PATENT OFFICE.

DONALD MURRAY, OF SYDNEY, NEW SOUTH WALES.

PRINTING-TELEGRAPH.

SPECIFICATION forming part of Letters Patent No. 498,674, dated May 30, 1893.

Application filed November 2, 1892. Serial No. 450,711. (No model.)

To all whom it may concern:

Be it known that I, DONALD MURRAY, of Sydney, New South Wales, have invented a new and Improved Printing-Telegraph, of 5 which the following is a full, clear, and exact description.

My invention relates to improvements in printing telegraph apparatus, and is designed, by means of a transmitting device provided 10 with an ordinary keyboard, such as the Remington, to operate at a distant station any ordinary typewriter, or other keyboard machine, such as a type setting machine, the Rogers typograph, or Mergenthaler's linotype. 15

The object of the invention, as illustrated and described in the accompanying specification, is to transmit any one of the thirty-two positive combinations of five short positive and negative currents corresponding in duration to the Morse dot to an interpreting instrument at a distant station, consisting of thirty two elements, one only of which is completely unlocked by any given combination 20 of currents, and being unlocked, makes electrical contact and operates a given electro-magnet and corresponding key of a typewriter. 25

The apparatus embodying my invention, 30 may, however, be provided with a greater number of combinations and of positive and negative currents, as hereinafter described.

The object of the invention is to fulfill the following conditions: first, to use only ordinary telegraph currents capable of being relayed and subject to all the conditions of ordinary telegraphy; second—to operate at a distance any ordinary typewriting machine or any type setting or similar machine; third— 35 to be able to transmit at least eighty different characters; fourth—to work at the utmost speed permitted by the manual dexterity of the operator working at a transmitting keyboard in all respects like that of an ordinary typewriter keyboard; and fifth—to dispense with all clockwork controlling mechanism, synchronously moving type wheels and other slow and cumbersome devices. 40

The invention consists practically of a duplication of two very simple elements, viz: first—a transmitting element, which, by the depression of a key, transmits a certain com-

bination of five short positive and negative currents; and second—an interpreting element, by the passage through which of a given 55 combination of positive and negative currents, a spring or lever is released and makes electrical contact, thus energizing a particular electro-magnet which operates a certain type key. Thirty two transmitting elements 60 connected in parallel form the transmitter, and thirty-two interpreting elements form the interpreter, and these combined and with a shift key device, a typewriter, and a battery all suitably connected, comprise the essential 65 features of the invention.

Reference is to be had to the accompanying drawings forming a part of this specification, in which similar figures and letters of reference indicate corresponding parts in all the 70 views.

Figure 1 is a diagram of the complete apparatus, showing two connected stations. Fig. 2 is a diagram of the transmitter. Fig. 3 is a cross section through the transmitter on the line 3—3 in Fig. 4. Fig. 4 is a broken plan of the transmitter. Fig. 5 is a detail cross section on the line 5—5 in Fig. 3, showing the arrangement of the transmitter contact button and the commutator. Fig. 6 is a diagram 80 of the interpreting instrument. Fig. 7 is an enlarged vertical section of the interpreting instrument, on the line 7—7 in Fig. 10. Fig. 8 is a detail front elevation of a modified means of moving the interpreting rack and 85 quadrant. Fig. 9 is a cross section on the line 9—9 in Fig. 8. Fig. 10 is a broken plan view of the interpreter. Fig. 11 is an enlarged detail plan of the switch which is arranged in the main line and controls the connections with the entire apparatus. Fig. 12 is a diagram of the shift key mechanism. Fig. 13 is a broken detail plan of the shift key mechanism. Fig. 14 is a broken detail section on the line 14—14 in Fig. 13. Fig. 15 90 is a detail perspective view of one of the pawls which lock the slide board or plate of the shift key mechanism. Fig. 16 is a modified form of mechanism for operating the typewriter keys, this construction being adapted for use in machines having a great number of keys, and in which considerable power is necessary to actuate the keys. Fig. 17 is 95 a modified form of apparatus for controlling 100

the shift keys of the machine, and Fig. 18 is a detail elevation and diagram of the mechanism for automatically returning the typewriter carriage after it has printed a line.

5 Referring to Fig. 1, which shows two stations marked 1 and 2 respectively, each station is provided with a transmitter 10, an interpreter 11, a shift key mechanism 12, a typewriter 13, or a keyboard machine used in lieu 10 of a typewriter, an automatic device 13^a for shifting the typewriter carriage, although the carriage may be shifted by hand as hereinafter described, a main switch 14, controlling the several circuits, a galvanometer 15 which 15 indicates whether or not a current is passing through the main line, and a signal bell 16. A battery A is arranged at station 1, and a battery A' at station 2.

The general operation of the apparatus will 20 be described, to make its principle thoroughly understood, after which the details of the different mechanisms will be fully explained.

Upon depressing the key of the transmitter 10 at station 1, the circuit is completed 25 and a current passes from the battery A, through the wire a, the wire b, the switch 14, the wire c, the transmitter 10, the wire d, the main line e, through the switch 14 at station 2, the wire f, the interpreter 11 at station 2, the 30 wires g, h and i to the earth, from the earth through the wire i at station 1 back through the wire h, the transmitter 10 and the wires p' and p, and the wire m to the battery A.

Along this circuit, by the internal construction 35 of the transmitter which will be herein-after described, a combination of five short positive and negative currents is sent to the interpreter 11 at station No. 2. By the construction of the interpreter, which will also 40 be described later, this given combination of five currents completes the circuit from the battery A', through the wire a, the wire b, the switch 14 at station 2, the wire j, the interpreter 11, the wire k and the wires l, m, back 45 to the battery A'. This local circuit, by the operation of the interpreter, sends a current along one of the thirty-two pairs of wires n 50 connecting the interpreter with the shift key mechanism 12, so as to operate said mechanism, and from said shift key mechanism the current goes over one of the eighty four wires, first to the typewriter 13, where it operates a type key corresponding to the transmitter key which was depressed. This process 55 is repeated every time the key of the transmitter is depressed. One of the transmitter keys operates the space key of the typewriter and three other transmitter keys operate the shift key mechanism 12, shifting 60 to capitals, lower case, or figures as the case may be. When the paper carriage of the typewriter comes to the end of a line, it can either be returned by the attendant at the receiving station, or it may be automatically 65 returned by the mechanism 13^a, as herein-after described. The galvanometer 15 on the main line at each station indicates when a

current is passing. The needles of each galvanometer may either indicate by sight whether a current is passing, or by ear, by 70 means of a very small bell the faint tinkling of which will be a sufficient indication to the transmitting operator that currents are passing while he operates the keys.

The next point to be described from the 75 diagram is the method by which the operators at stations 1 and 2 signal to one another to stop or prepare their instruments for receiving. For this purpose it is necessary to describe first in detail, the construction of the 80 switch 14. This construction is shown on a large scale and in detail in Fig. 11. A triangular lever 17 is pivoted on the switchboard, as shown at 18, and provided at the end of one arm with a knob 19, by which it may be 85 turned, and this knob or handle arm moves over a graduated scale 20, which serves to indicate the different positions of the switch, and the switch has another arm arranged to make contacts with the points 21 and 21^a, 90 which are connected with the wires c and j of the transmitter and interpreter 10 and 11. The switch arm has an insulated cross bar 22 connected with the second switch arm 23, which is also pivoted on the switchboard, as 95 shown at 24, and the free end of this arm 23 is adapted to make contact with the points 25 and 25^a, connecting respectively with the wire f of the interpreter and the wire d of the transmitter. The switch also connects as already described, with the wire b which connects with a battery and with the line wire e. On the pivot 24 is also a switch 26, which normally swings out of contact, but which may be pressed against a contact 27, so as to 105 connect through the wire i with the earth. The wire i is also adapted to connect with the wires p, and consequently with the batteries A or A', by a switch 28. It will be seen that this arrangement causes the switches 23 and 110 17 to be moved together, parallel movements being given to the two switch arms by the cross bar 22.

To work the instrument for signaling, we 115 will suppose that an operator is sending a question from station 1 by the transmitter to station 2, and that the attendant at station 2 wishes for some reason to stop it. The latter moves the switch key at station 2 so as to break contact at 21, 21^a, 25 and 25^a, and make 120 contact with the line at 25^b; the result is, that until the switch 28 next the bell 16 at station 2 is closed, the circuit is broken and the galvanometer 15 at station 1 indicates that a current is no longer passing. The attendant at 125 station 2 then closes the switch 28, and by this means the battery A' is put in direct connection with the main line and the earth, the current passing through the wires m and p, the switch 28 and the wire i. The operator at 130 station 1, noticing by the galvanometer that no current passes on pressing the transmitter key, presses the switch button 26 of the switch 14 at station 1, which puts the main line to

earth and rings the bell at station 2, thus indicating that he has noticed the signal. He then shifts the shift key in the switch 14 from the contact points 21^a and 25^a to the contact points 21 and 25, thus throwing the interpreter into action. The attendant at station 2 on hearing his bell 16 ring, shifts his switch 23 from the contacts 21 and 25 to the contacts 21^a and 25^a, thus throwing his transmitter into action. Station 2 is thus converted into a transmitting station and station 1 into a receiving station. The attendant at station 2 can now send the required message through to the operator at station 1, by means of the transmitter, interpreter and typewriter as previously described. This operation can be performed from either end, and though complicated in description is very simple and rapid in practice. If desired, the switch 28 can be embodied in the switch 14.

When the instruments are not in use the bells are put in circuit as described. The operator at either station can then call up the other station by pressing the button 26, this operation ringing the bell by closing the circuit through it. If preferred, the interpreters at each station can be left in the circuit. An operator at either station can then by switching his transmitter into the circuit, send a message to the other station, where it will be recorded on the typewriter without an attendant being present, the process being automatic and only the necessary precaution being taken that a sufficient amount of paper is in the typewriter to receive the message. It will be readily seen too, that if desirable, the message transmitted, say from station 1 to station 2, may be recorded on the typewriter at station 1 as well as at station 2, thus preserving a record. This can easily be effected by passing the current combinations from the transmitter at station 1 through the interpreter there as well as through the interpreter at station 2. It will be seen that all the alteration necessary will be a slight change in the switchboards, and as this does not affect the invention it is not shown in the drawings.

When the apparatus is used for operating a typesetting or other similar machine, such a machine takes the place of a typewriter and the mechanism 13^a for shifting the current is dispensed with. If the typewriter carriages at both stations are not operated automatically when a message is transmitted, then a small register is needed at each transmitter to count the number of keys depressed and ring the bell when the carriage nears the end of a line. This warns the operator to cease transmitting for a moment until the carriage is returned.

The internal mechanism of the different portions of the apparatus will now be described. The transmitter (see Figs. 3 to 5) is provided with a suitable base 35, having a supporting framework 36 thereon, and in this are vertically sliding key rods 37, having fin-

ger pieces 38 at their upper ends, which finger pieces are marked in the same way as the keys of a typewriter or other machine with which the transmitter connects. These key- rods are held to slide in guides 39 and 39^a (see Fig. 3) and on the rods are collars 40, which engage the ends of springs 41, and the latter are curved outward and bent at a right angle, and their lower flat portions 42 carry insulating contact blocks 43, which blocks have beveled upper portions 44, adapted to fit against the beveled lower portions 45 of the commutators 46, which commutators have inclined upper ends 47 and pairs of V-shaped grooves 48, arranged vertically and parallel with each other.

By reference to Fig. 5, it will be seen that the contacts 29 and 29^a are produced on the insulating blocks 43, and the several contacts 30, 30^a, 31, 31^a, 32, 32^a, 33, 33^a, and 34, 34^a, are produced in the grooves 48 of the commutator. The contact points 29, 29^a, and the several stationary contacts are connected up in substantially the manner already described, the contacts 29, and 29^a connecting by the wires d' and h', with the wires d and h, (see Figs. 1 and 2) and the several contacts 30, 30^a to 34, 34^a, are connected in parallel by the wires c' and p' with the wires c and p', shown in the diagram Fig. 2.

By reference to the diagram Fig. 2, it will be noticed that a portion of the stationary contacts are crossed as shown at 34, 34^a at the left hand of the diagram, and that the combination of positive and negative currents will depend upon the number of these connections that are crossed. Consequently when the contacts 29 and 29^a are moved across the contacts 30, 30^a to 34, 34^a, a series of short vibrations are sent over the line wire, which are positive or negative according as the wire connections of the stationary contacts are crossed or not. It will be seen that when the connections are crossed, as shown at 34, 34^a, Fig. 2, the current goes in the reverse direction to that it does when the other contacts are made.

It may be remarked here that five positive and negative currents are the least number that are of service, for four would only give sixteen combinations, whereas at least thirty are required. Five will give thirty-two combinations, allowing one combination for operating the space key of a typewriter, and one each for the change to capitals, lower case or figures. There are twenty-eight combinations remaining for transmitting letters or figures. As there are three shift keys for capitals, lower case and figures, we can multiply these combinations by three, giving eighty-four as the possible number of letters and figures capable of transmission by thirty-two keys, including three shift keys.

The machine is not necessarily limited to combinations of five positive and negative currents, as it will be readily seen that six or seven or even more may be used if necessary,

but a greater number of combinations makes the machine too cumbersome and complicated.

The action of the transmitter is as follows: When one of the finger pieces 38 is depressed, 5 the corresponding key-rod 37 slides downward and the contact block 43 slides down the inclined top surface 47 of the commutator 46, as best shown in Fig. 5, until the block reaches the lower beveled surface 45 of the commu- 10 tator, which surface it will be seen is arranged at right angles to the top incline 47, and when the block reaches the inclined surface 45, it springs inward, and guided by said surface 15 clicks beneath the commutator and against the guide 49, which prevents too much vibration of the block. Upon releasing the key, the spring 41-42 raises it and causes the block to pass over the face of the commutator, so that the contacts 29 and 29^a make suc- 20 cessive contacts with the fixed contacts 34, 34^a to 30, 30^a, and a series of positive and negative vibrations are sent over the line. It is better that the sending contacts be made during the up-stroke of the keys, as 25 the spring causes a more even movement to be made automatically than can be produced by hand. The vibrations pass from the transmitter of one station to the interpreter of the next as already described, and 30 the action of the interpreter may be understood in a general way by referring to the diagram in Fig. 6. A few elements only of the interpreter are shown, as they are all alike, and its action will be readily understood. 35 The interpreter is run on a local circuit supplied by a battery B, and it is provided with a series of interpreting electro-magnets 50, there being a magnet for each letter or character represented. The main line current 40 passes through these magnets, the current entering through the wire f, and passing successively through the wires f', f², f³ and the several interpreting magnets, and through the wire g to the earth. At each electro- 45 magnet 50 is a pair of oppositely polarized detents 51, which are centrally pivoted, as shown at 52, and which have at one end hooks 53 to engage the interpreting quadrants 54, the opposite ends being held to vibrate between 50 the poles of the magnet. As the detents are oppositely polarized, a positive current through the magnet will affect one without affecting the other, and vice versa. The interpreting quadrants 54 are provided with 55 rows of teeth on their upper surfaces, and the teeth are dissimilarly spaced in each row, and the teeth are also dissimilarly arranged on each quadrant from the arrangement on any other quadrant. The consequence is, 60 that when a current passes from the main line through one of the magnets 50, one lever is attracted upward and the other downward. Any particular quadrant will only be released by a combination of positive and nega- 65 tive currents corresponding to the arrangement of the teeth on the quadrant, that is,

supposing the quadrant to have the following combination of teeth, left, right, right, left, right. This quadrant will then only be completely released by a corresponding combination of positive and negative currents, namely, - + + - +. The action of the current on the levers will be better understood by reference to Figs. 7 and 10, and the construction of the interpreter will be hereinaf- 75 ter described.

It will be seen that only a certain combination releases a quadrant, and the same combination of currents may pass through all the other electro-magnets without affecting any other quadrant. The quadrants are supported upon springs 55, and the tension of the springs is such that when the quadrant is released, it results in a contact being made at 56, and the electric circuit is closed 80 through the wires p², q, the magnet 57, which is arranged beneath the corresponding key of a typewriter or other keyboard machine, the wire q', the wire r, one leg of a magnet 58, the wire r', the quadrant 54, the spring 55, and 90 the wire p³ back to the battery B. The closing of this circuit energizes the lower leg of the magnet 58, which then attracts the spring armature 59. The armature 59 consists of a very light spring adjusted as close as possible 95 to the poles of the electro-magnet 58, without actual contact, in order that it may when attracted, make contact with the poles of the electro-magnet as rapidly as possible. This armature 59 being attracted, makes contact 100 through the poles of the electro-magnet, and by so doing it closes the alternative circuit through the wires s and s', one end of the wire s being secured to the upper leg of the magnet. Consequently, when the armature 59 is at- 105 tracted by the lower leg, it makes electrical contact with the upper leg, and the current in addition to closing the alternative circuit, by attracting the armature, has also begun to operate the typewriter electro-magnet 57 110 and the electro-magnet 60. This latter mag- 115 net, as will be subsequently explained, when energized, throws back the interpreting quad- 120 rant and allows it to be again caught and re- 125 tained by the lever detents 51. The result of this is that the line circuit shown by the wires f and g, is broken, and the whole current passes by the alternative path through the wire s, the armature 59 and the wire s', the armature 59 being retained in contact by the 130 upper leg of the magnet 58. When the armature of the magnet 60, to be subsequently described, makes contact with the poles of the magnet, the current from the battery B is short circuited, the current passing through 135 the wires s² and s³. The result is that all the electro-magnets are de-energized, and conse- 140 quently all the circuits are broken including that made by the armature 59, which being no longer attracted, flies back to its normal 145 position. This action is repeated each time a combination of currents passes through the

main line. The success of the machine depends on the rapidity with which this action can take place.

The object of the electro-magnets 58 is to enable the magnets 57 and 60 to make a complete stroke. Without the magnets 58, and with the current going direct from the wire q' (see Fig. 6) to the contact 56, the only result of the quadrant 54 making contact at 56 is to set up a violent buzzing like the trembling of an electric bell. This difficulty may be avoided in different ways, but the arrangement shown is the simplest and best.

Fig. 7 shows a single element of the interpreter, and Fig. 10 shows several elements in plan. Referring to Fig. 7, the details of the connections may be more readily seen. The construction of the interpreter is also shown in this figure and in Fig. 10, and it will be noticed that the polarized detents 51 are pivoted on a supporting base 61, which is fastened by a screw 62 to a supporting block beneath. The action of the interpreting quadrant is also more clearly seen in Fig. 7, and it will be seen that when the combinations of currents tilt the detents and release the quadrant, the spring 55 straightens up and makes contact with the spring 56, as already described. When the contact is made at 56 (see Fig. 7) the circuit is closed from the battery B, through the wire p^3 , the wires q and q' , including the magnet 57 of the typewriter, the wire r , the spring 55, the wire s^3 , the lower leg of the magnet 58, the wire s^4 , the magnet 60, the wire s^5 and wire s^2 back to the battery. This circuit is like that already described and shown in Fig. 6, but the connections are shown more in detail. The consequence is that the spring armature 59 is attracted and makes contact with the poles of the magnet 58 and completes the alternative circuit through the upper coil of the magnet, and through the magnet 60, as already described. Owing first, to the almost entire absence of inertia in the armature 59, second—to the very short distances through which it has to travel before making contact, and third—to the small size of the electro-magnet 58, consisting as to its base of two or three coils of 50 coarse wire on a core composed of a couple of inches of No. 8 iron wire, this alternative circuit is established almost instantly the moment the quadrant makes contact with the spring 56. From the instant the quadrant makes contact the electro-magnet 60 begins to be energized and to attract the armature 63, which is secured by means of cranks 64 to a shaft 65, and the shaft is rocked so as to tilt the rocking lever 66 and cause its upper 55 insulated end 67 to engage the spring 55 and push the quadrant 54 back into engagement with the locking detents. The upper end of the lever 66 is insulated, as shown at 67, to prevent short circuiting. The current of the battery B thus short circuits as follows: the wire s^7 , the armature of the magnet 60, the weight 63, shaft 65, wire s^6 , and the wire s^2 to

the battery. The electro-magnets, including the magnets 57 which operate the typewriter keys during the period of the attraction of the armature 63, are thus de-energized, the spring armature 59 flies back, breaking the circuit, and the spring 77 described below, draws the armature 63 away from the magnet 60. The element is now ready to interpret a fresh combination of currents through the main line.

The action described above takes place in each of the thirty-two elements of the interpreter, but it will be understood from the previous description that but one quadrant will be released, which quadrant has its teeth arranged to correspond with a particular combination of currents which act through the magnet 50 on its polarized detents 51.

The shaft 65 is arranged at right angles to the series of magnets 50 (see Fig. 10) and it connects by means of a pitman 68 and crank 69 with a parallel shaft 65^a, arranged adjacent to a second row of magnets 60, and it will be understood that any necessary number of shafts may be connected in this way, the number of magnets, pairs of detents and quadrants corresponding with the number of characters and shift keys. The interpreter is provided with a suitable supporting bed 70, on which all the apparatus comprising the interpreter is carried, the shafts 65 and 65^a turning in suitable bearings beneath the bed, and the levers 66 moving in slots 66^a in the bed. The several magnets are supported on blocks 71. On the upper leg of each magnet 50 is an outwardly-extending lug 71^a, in the outer end of which is a vertical screw 72, held threaded in the nut 73, which is held to turn in the lug 71^a, and the screw has its lower end secured to a spring 74 attached to the detent 51, and the tension of the spring pulls the detents up against one of the magnetic blocks 62^a on the under side of the upper leg of the magnet, (see Fig. 7.) These blocks may be made of lead, brass or other suitable material. In a flange of the bed 70, opposite the magnet 60, is a screw 75 on which is a nut 76, and this nut is secured to the spring 77, the opposite end of which is attached to the armature 63, and by means of the nut the tension of the spring may be very nicely regulated.

The pairs of coils forming the interpreting magnets 50 do not need many turns of wire to perform the comparatively slight work required of them, but as there are thirty-two pairs of them considerable resistance is offered by them to the feeble currents coming over a long stretch of the main line. The local battery does not come into use till the work of the main line current is done and the quadrants are released, when it is at liberty to be used for relaying the main line current to operate the interpreting magnets. When the spring 55 is used to support the quadrant 54, it is provided with a turned-up flange 55^a at the bottom, through which a fastening screw 78 extends, (see Fig. 7) and a second screw

79 extends up through the bed 70 and impinges on the flange of the spring so that by turning the screw, the position of the spring may be adjusted to enable it to have the correct tension.

In Figs. 8 and 9, I have shown means for supporting the interpreting quadrants which is more reliable than the spring 55, but I do not confine my invention to the use of either 10 of the forms of mechanism shown. In this case, the quadrant 54 is secured to an arm 80, which terminates at one end in a sleeve 81 held loosely on the shaft 65 or 65^a as the case may be. The sleeve 81 has a shoulder 82 on 15 one side adapted to engage the free end of a spring 83, which is secured to an adjacent support 84. A crank 84^a is secured to the shaft 65, and is also bent to extend parallel with the shaft and opposite the arm 80. When 20 the detents 51 are released in the manner already described, the tension of the spring 83 throws the sleeve 81 around and swings the arm 80 in a manner to carry the quadrant 54 into engagement with the contact 56. When 25 the shaft 65 is returned by means of a mechanism substantially like the armature 63 and magnet 60, the crank 84^a strikes the arm 80 and carries the quadrant back into engagement with the detents.

30 The next thing to be described is the shift key mechanism. In the case of typewriters like the Hammond, which have shift keys for both capitals and figures, a separate shift key device is not necessary. But what is needed 35 is an electro-magnet to operate the capital shift key, another to operate the figure shift key, and a third to bring the machine back to lower case. In the case of bar-lock and other machines with seventy or eighty keys, 40 where seventy or eighty large electro-magnets would be a heavy expense and there would be difficulty in finding room for them, the mechanism shown in Fig. 16 is used. Here, 45 85 represents a key of the typewriter and 86, a lever which at one end terminates in a sleeve 87, held to rotate freely on the shaft 65. The free end of the lever connects by links 88 and 89 with the key 85. A spring 90 is attached to the lever by a screw 91, and 50 overlaps the sleeve 87, the spring having a pin 92 upon it which enters slots 93 in the sleeve and shaft 65, and when the two register, the pin locks the lever 86 to the shaft. When a signal has been interpreted and the 55 interpreter sends a current through the small magnet 94, the armature 95 on the end of the spring 90 is pulled down, and the pin is forced into the recess 93 in the shaft and sleeve. The device is arranged so that by the contact 60 of the armature 95 with the magnet 94, a circuit is closed which energizes a large magnet, such as the magnet 60 already described, which magnet is arranged to rotate the shaft 65 in a similar manner, and consequently motion will be communicated to the typewriter 65 key operated.

In the case of machines like the Ham-

mond, with only thirty-two keys arranged in a semicircle, a small electro-magnet may be provided for each key, and for this purpose an 70 electro-magnet of the iron clad semi-solenoid type, such as shown in Fig. 17 is especially applicable. Here the magnets 96, 96^a and 96^b are shown with plunger armatures 97, 97^a and 97^b. The plunger 97 is pivoted at the 75 top, as shown at 98, to the capital shift key 99, and the plunger 97^b is pivoted in a similar way to the figure shift key 100. The plunger 97^a, whose duty it is to bring the machine back to lower case printing, has at the top a 80 post 101 with studs 102 thereon, between which the free ends of the diverging levers 103 are held. These levers are pivoted at 85 points near the keys 99 and 100, as shown at 104, and on the same pivots are pawls 105, terminating at their upper ends in hooks 106. The movements of the pawls are limited by 90 shoulders 107 on the lower ends of the pawls and studs 108 on the levers 103, and the pawls are pressed into engagement with the keys 99 by springs 105^a. The keys 99 and 100 are provided with vertical transverse grooves 109, which thus form catches at the bottom to engage the hooks of the pawls 105, and the pawls are also adapted to engage the top edges of the 95 keys. The plunger 97^a is normally pressed upward by a spring 97^c, and the other plungers are raised by the ordinary springs of the 100 keys 99 and 100. Suppose that the key 100 is up like the key 99, and that the operator 105 wishes to print some figures. He depresses a key at the transmitting station, which sends a combination of currents, which by means of the interpreter sends a current through the 110 electro-magnet 96^b, and the latter sucks down the plunger 97^b and key 100, and the pawl 105 springs outward so that its hook 106 engages the top of the key and holds it down. The typewriting machine will thus be in position 115 to print figures. When the operator 120 wishes to return to the lower case again, he presses the transmitting key which energizes the electro-magnet 96^a; the plunger 97^a is sucked down, the levers 103 depressed, the 125 stud 108 thrown into engagement with the shoulder 107 of the pawl 105, and the latter is tilted out of engagement with the key 100 so as to permit the key to rise. If capitals are 130 to be printed the magnet 96 is energized and the key 99 is drawn down and engaged in the 135 manner just described.

For instruments having more than thirty-two keys, such as bar-lock, caligraph and type-setting machines, a different arrangement is necessary. Fig. 12 is a diagram showing the 140 arrangement of circuits for this purpose. 110, is a switchboard which slides forward and back on a fixed board 111; one of the contact points 112 and 112^a, is adapted to make contact with the fixed contacts 113, 113^a, 114, 114^a, 115, 115^a. The contacts 112, 112^a, are connected with the wires *n'* and *n^a*, which are adapted to be arranged in the circuit according to the diagram (see Fig. 12) and the other

contacts connect with wires o' and o^2 , leading to the shift key magnet 57. The construction by which this arrangement is carried out is shown in Figs. 13, 14 and 15.

5 In Fig. 13, I have shown the magnets 116, 117, 118, which form the capital, lower case and figure shift keys. 119 (see Fig. 14) is a stationary board with four rows of contact buttons 120 arranged in groups of three, making in all eighty-four contacts corresponding to eighty-four keys of the typewriter. This grouping is not shown in detail, but it will be readily understood. Wires u lead from these contacts and are adapted to connect up according to the diagram already described, the wires being adapted to lead to the electromagnets of the typewriter keys. Beneath the board 119, is a sliding switchboard 121, having contact springs 122 arranged preferably in four rows with seven in a row, each corresponding to three of the contact buttons in the board 119. These springs are attached to the board by screws 123, which project through the board and are attached on their under sides to spiral springs 124, which are held above another stationary board 125, and which connect with wires u' and are adapted to connect with the interpreter in the manner already described. When the board 121 is in the normal position, completing the circuits printing lower case, the springs 122 make contact with one of the buttons 120, as shown at x in Fig. 14, and when the board is moved to the left, contact is made with the buttons shown at x' , thus shifting the capitals, and when moved to the right, contact is made as shown at x^2 , thus shifting for figures. The springs 124 allow the necessary freedom of movement. The result of this arrangement is that the twenty-eight wires in the stationary board 125, can be connected with three different sets of wires in the stationary board 119, according to the position of the board 121.

Referring again to Fig. 13, the mechanism for shifting the board 121 may be seen in detail. The board has at opposite ends iron armatures 126, with beveled ends 127 held to move in grooves in side supports 128. Extending longitudinally across the board is a rod 129, in the center of which is a stud 130, and this is held to move between two springs 131, which are secured to a support at the side of the board, as shown at 132, and the tension of the springs is such as to act on the stud 130, and hold the board normally in position for lower case printing, that is, with the contact springs 122 on the buttons 120, as shown at x in Fig. 14. The switchboard 121 is held in position against the magnet 116 or 118 by one of the pawls 133 or 134, which are arranged at one side of the switchboard, and which have near their free ends shoulders 135 which engage a notch 136 in the side edge of the switchboard. The pawls are pivoted on supports 137 adjacent to the switchboard and are pressed into engagement with the latter by springs 138, which are secured to the sup-

ports 128. The pawls 133 and 134 are arranged opposite the magnet 117, and act as armatures, so that when the magnet is energized, the pawls are pulled out of contact with the switchboard. When the typewriter or other keyboard machine is to be set for lower case work, the magnet 117 is energized, and the pawls 133 and 134 are pulled against the magnet so that the springs 131 acting on the stud 130 center the switchboard and bring the springs 122 in contact with the buttons 120, as at x , thus adapting the machine for lower case. If the machine is to be set for capitals, the magnet 116 is energized, which is done by depressing the proper shift key on the transmitter at the opposite end of the line, as previously described, and the magnet acting on the armature 126, 85 pulls the switchboard 121 to the left until the tooth or shoulder 135 on the pawl 134, enters the notch 136 in the switchboard, and the pawls thus serve to hold the switchboard in position for printing capitals, that is, it holds 90 the contact springs 122 upon the buttons 120, as shown at x' , and the capital shift key of the typewriting machine is acted upon in the manner already described. If figures are to be printed, the magnet 118 is energized in the 95 manner above explained, and the switchboard 121 is pulled to the right, thus shifting the contact springs onto the buttons 120, as shown at x^2 , and sending the current through the figure shift key magnets, as 96^b, so that 100 the typewriter is set to print figures. It will be seen then that the mechanism shown in Figs. 13 and 14, is adapted to work by shifting the currents through the several magnets so as to switch the circuit through either of the key 105 controlling magnets of the typewriter or other keyboard machine, and the whole affair is controlled by the transmitter at the opposite end of the line.

The typewriter paper returning mechanism, 110 marked 13^a in the diagram, is shown clearly in Fig. 18. This is not a very essential part of the invention, as the attendant at the receiving station can return the paper carriage, but if it is desired to have the action at the 115 receiving station completely automatic, suitable mechanism for the purpose can easily be arranged on some such principle as the following: In the bar-lock capital typewriters, one motion of the lever both turns the paper 120 to a fresh line and returns the carriage ready to start at the beginning of another line. In any of the typewriters a cord or chain can be arranged so that on being pulled through a certain distance, it will perform the main operation of turning a line and returning the carriage, acting similarly to the cord and spring barrel on most typewriting machines. Consequently the mechanism required is simply such as will wind up a cord, for, say, twelve 130 inches, and then leave it free to unwind again until the twelve inches are paid out, when the device must again automatically start to wind, and so on.

In Fig. 18, an arrangement for doing this is clearly shown. C, is the battery for actuating the parts, and 139 is a ratchet wheel secured to a shaft 140, which is journaled in a suitable supporting frame 140^a. On the same axle is a winding drum 141, shown by dotted lines in Fig. 18, and to this drum is secured the operating cord 142, which is adapted to be wound upon and unwound from the drum. 10 Near the ratchet wheel and on a lower plane, is a magnet 143, which actuates an armature 144 above it, and this armature is secured to a click lever 145 which is pivoted at one end, as shown at 146, and is adapted to engage the 15 teeth of the ratchet wheel, and turn it by a step-by-step movement. The armature and click lever are normally held up by a spring 147, which is secured to a stud 148 and held beneath the stud 149, and the pressure of the 20 spring throws the click-lever upward into contact with a contact stud 147^a, so as to close a circuit which will be described below.

The ratchet wheel is held from turning in the wrong direction by a pawl 150, which is 25 pivoted near its center, as shown at 151, and is pressed into engagement with the ratchet wheel by a spring 152, and the pawl has an outwardly-extending shank which is restricted in its movement between studs 153 and 30 153^a, the latter serving also as a fastening for the spring 152. On the same pivot 151 with the pawl, is a lever 154, which at its upper end is forked, as shown at 155, so as to receive the operating cord 142. The cord is provided with buttons 156, which are spaced so as to strike the lever 154 first on one side and then on the other, these buttons being the distance apart corresponding to the movement of the cord, and in the drawings, but one button is shown, as the other is supposed to be wound upon the drum 141. Near the lever 154 are two contacts 157 and 158, one of which is connected with the battery C, as described below.

45 The operation of the winding device is as follows: When the typewriter carriage approaches the end of a line and the cord 142 has been unwound from the drum, one of the buttons 156 strikes the lever 154 and throws it over from the insulated contact block 158 to the block 157. The click-lever 145 being in contact with the stud 147^a, and the lever 154 on the block 158, the following circuit is maintained: from the battery C through the wire v, the click lever 145, the contact 147^a, the wire v', the lower leg of a magnet 159 which is arranged in connection with the apparatus, the wire v², the wire v³ out to the transmitter or line, and the wire v⁴ back to the battery. 50 The current passing through one leg of the magnet 159, draws the spring armature 160 of said magnet against the poles of the magnet. When the lever 154 is carried by the button 156 from the block 158 to the block 157, another circuit is established, which is as follows: from the battery C through the wires v and w, the contact block 157, the lever 154, the

wire w', the upper leg of the magnet 159, the armature 160, the wire w², the magnet 143, and the wires v³ and v⁴ to the battery. Although 70 the resistance of this alternative or last circuit is considerably greater than on the other, still sufficient electricity passes through the magnet 143 to just break contact of the lever 145 with the stud 147^a. The whole of 75 the current then passes over the second circuit and through the magnet 143, which powerfully attracts the armature 144, and the click lever 145 pulls round the ratchet wheel. When the armature makes contact 80 with the magnet 143, the current short circuits as follows: from the battery C through the wire v, the lever 145, the armature 144, the magnet 143, the core of the magnet, the wire w³, and the wires v³ and v⁴ to the battery. If 85 the wires on this new circuit are short and stout, practically the whole of the current will pass over it, and the electro-magnets 143 and 159 will be de-energized and their armatures released. The spring armature 160 being released, breaks the circuit and allows the lever 145 to be raised again into contact with the stud 147^a. When the lever 145 comes in contact with the stud a circuit is again established through the lower leg of the magnet 95 159; the armature 160 is again attracted and the operation above described takes place again, so that the ratchet wheel is pulled around sufficiently to wind the cord 142 upon it. 100

From the foregoing description, and the description of the method of operation given in the earlier part of the specification, the invention will be clearly understood.

Having thus described my invention, I 105 claim as new and desire to secure by Letters Patent—

1. An apparatus of the character described, comprising a keyboard machine such as a typewriter or a type-setting machine, a transmitter adapted to send vibrations over a wire and an interpreter connected with the transmitter and keyboard machine, the interpreter comprising a series of electro magnets adapted to connect with the transmitter, circuit 115 closing swinging toothed quadrants arranged adjacent to the magnets and adapted, when released, to close a circuit through the keys of a keyboard machine, and locking detents arranged to contact with the quadrants and hold the same in locked position, the detents being operated by the electro magnets, substantially as described.

2. An apparatus of the character described, comprising keyboard machines such as type-writers or type setting machines arranged at 125 opposite ends of a line, an interpreting machine at each end of the line, electro-magnetic means for operating the keys of the keyboard machines, an electrically operated switch or 130 shift key mechanism adapted to send the current through certain keys of the keyboard machine, electrical connections between the shift key switch and the interpreter, a trans-

mitter arranged at each end of the line and connected with the interpreter at the opposite end of the line, the transmitter being adapted to send for each character represented a certain combination of positive and negative currents, and automatic means arranged within the interpreter and actuated by the combination of positive and negative currents whereby the shift key switch is operated so as to actuate the corresponding key of the keyboard machines, substantially as described.

3. In an apparatus of the character described, the transmitter comprising a commutator or board having a series of contacts thereon, arranged in pairs and with direct and crossed connections with the line, and a key operated insulated contact block carrying contact points adapted to move over the pairs of contacts on the commutator and close the circuit through the same, substantially as described.

4. In an apparatus of the character described, a transmitter, comprising a commutator having rows of stationary contacts thereon arranged in pairs and connected in parallel with certain of the connections crossed, and a sliding key-operated contact block having contacts thereon to engage the stationary contacts and close the circuit through the same, the contact block being adapted to move over the commutator on the up-stroke of the key, substantially as described.

5. In an apparatus of the character described, the transmitter comprising a commutator having on one side parallel rows of stationary contacts connected in parallel with the line and having a portion of the connections crossed, the commutator having its top surface inclined and its lower surface inclined at right angles to the inclination of the top surface, a key held to slide adjacent to the commutator, and a contact block having a spring connection with the key and carrying contacts adapted to connect with a source of electricity, the contact block being arranged to move downward on one side of the commutator and to slide inward and move upward so as make contact with the contacts of the commutator, substantially as described.

50 6. In an apparatus of the character described, the interpreter, comprising a series of electro-magnets corresponding with the number of keys in a keyboard machine with which the interpreter is connected, the interpreter being also adapted to connect with the line wire, a series of circuit closing quadrants having teeth thereon, the teeth of each quadrant being arranged in a different combination from those of any other quadrant, and locking detents pivoted adjacent to the poles of the electro-magnets and held to normally engage and lock the quadrants, substantially as described.

7. In an apparatus of the character described, the interpreter, comprising a series of electro-magnets adapted to connect with a line circuit closing and swinging quadrants

arranged adjacent to the electro-magnets and adapted when released to close the circuit through mechanism for operating a key of a keyboard machine such as a typewriter, each quadrant having a series of teeth thereon arranged in a different combination from the teeth of any other quadrant in the series, swinging detents adapted to be actuated by the electro-magnets and held to engage the teeth of the quadrants, and electrically and automatically rotated shafts adapted to be set in motion by the closing of the circuit in which the quadrants are arranged and carrying mechanism to return the quadrants to locked position, substantially as described.

8. In apparatus of the character described, the interpreter, comprising a series of electro-magnets adapted to connect with a line, swinging quadrants arranged adjacent to and opposite the magnets and adapted to swing and close the circuit through key-operating mechanism of a keyboard machine such as a typewriter, the quadrants having each row of teeth arranged in combinations dissimilar to the combinations of teeth on any other quadrant, and polarized detents arranged in pairs opposite each electro-magnet, the detents having hooks at one end to engage the teeth of the quadrant and hold the same locked, and their opposite ends held to swing between the poles of the magnets, substantially as described.

9. In an apparatus of the character described, the combination of the interpreter magnets, the swinging quadrants held loosely on a shaft and arranged to swing opposite the magnets, the quadrants being pressed by a spring and adapted to close a circuit through key-operating mechanism of a key-operated machine such as a typewriter, rows of teeth produced upon each quadrant so that each quadrant has a different combination of teeth from that of any other, polarized detents arranged in pairs to engage the teeth of the quadrants, the detents being released by combinations of currents in the magnets, and returning cranks secured to the shafts and adapted on a movement of the shaft to engage and swing back the quadrants into engagement with the detents, substantially as described.

10. In an apparatus of the character described, the interpreter, comprising a series of electro-magnets adapted to connect with the line, swinging circuit closing quadrants arranged opposite the magnets and adapted to close a circuit through key-operating mechanism of a keyboard machine such as a typewriter, the quadrants having rows of teeth thereon arranged in different combinations for each quadrant, polarized detents arranged in pairs to hold the quadrants in locked position, the detents being released by certain combinations of currents in the electro-magnets, a second series of electro-magnets arranged in a shunt circuit and adapted to hold the circuit closed through the released quad-

- rant and the connected key-operating mechanism until a character is printed, an electro-magnet arranged in a local circuit and adapted to return the released quadrant to a locked position and break the circuit through the key-operating mechanism, and automatic mechanism for short circuiting the interpreter and cutting out the interpreting mechanism, substantially as described.
11. In an apparatus of the character described, the combination, with the shift keys of a keyboard machine such as a typewriter, of a series of magnets arranged beneath the keys and in an electrical circuit, the armatures of the magnets being pivotally connected with the upper case and figure shift keys of the machine, and the lower case magnet being arranged between the upper case and figure magnets, locking pawls arranged adjacent to the upper case and figure keys and adapted to engage the keys when depressed, and levers operatively connected with the armature of the lower case magnet and adapted by the depression of the magnet to release the locking pawls, substantially as described.
12. In an apparatus of the character described, the shift key mechanism comprising electro-magnets arranged to operate the keys of a keyboard machine such as a typewriter, a series of stationary contacts connected electrically with the magnets of the keyboard machine, a movable switchboard connected with a source of electricity and having contact springs to touch the stationary contacts, electro-magnets arranged to operate armatures at opposite ends of the switchboard so as to move the latter, locking armature pawls held at one edge of the switchboard and adapted to engage the same and hold it in engagement with either of the electro-magnets at its ends, and a third electro-magnet arranged in an electric circuit and adapted when energized to release the pawls, substantially as described.
13. In an apparatus of the character described, the shift key switching mechanism, comprising a series of contact buttons ar-

ranged in groups and adapted to connect electrically with magnets for operating the keys of a keyboard machine such as a typewriter, a sliding switchboard having spring contacts connected with a source of electricity and adapted to touch the stationary contact buttons, the board having armatures at its opposite ends, magnets arranged opposite the armatures of the board and adapted when energized to slide the board, springs arranged to engage the stud on the board and hold it normally in a central position so as to connect with the lower case operating mechanism of the keyboard machine, locking armature pawls pivoted at one side of the switchboard and adapted to engage the same and hold it against either of the end magnets, and a third magnet arranged opposite the armature pawls and adapted when energized to move the same and release the board, substantially as described.

14. In an apparatus of the character described, the carriage returning mechanism, comprising a revoluble shaft having a drum thereon, a cord secured to the drum and adapted to connect with the carriage of a machine, spaced buttons secured to the cord, a ratchet wheel secured to the same shaft with the winding drum, an electro-magnet arranged adjacent to the ratchet wheel, a spring repressed armature lever held opposite the magnet and adapted to engage the teeth of the ratchet wheel, contact blocks arranged adjacent to the cord, one being connected with a source of electricity, and the swinging lever pivoted adjacent to the ratchet wheel and having a forked end to embrace the cord and extend into the path of the buttons thereon, the lever being also arranged to engage the contact blocks and make and break the circuit with the ratchet-operating electro-magnet, substantially as described.
